Primary Examiner — Samantha Wood*Assistant Examiner* — Aula Soroush(74) *Attorney, Agent, or Firm* — Grogan, Tuccillo & Vanderleeden, LLP(57) **CLAIM**

The ornamental design for a pet dental chew, as shown and described.

DESCRIPTION

FIG. 1 is a perspective view of a pet dental chew showing the new design;

FIG. 2 is a front view thereof;

FIG. 3 is a back view thereof;

FIG. 4 is a left-side elevation view thereof;

FIG. 5 is a right-side elevation view thereof;

FIG. 6 is a top view thereof; and,

FIG. 7 is a bottom view thereof.

The broken lines illustrate a break in length in the pet dental chew that forms no part of the claimed design. The surface between the break does not form part of the claimed design.

1 Claim, 2 Drawing Sheets(56)
